UNITED STATES PATENT OFFICE.

LEWIS C. BAYLES, OF EASTON, PENNSYLVANIA, ASSIGNOR TO INGERSOLL-RAND COMPANY, OF NEW YORK, N. Y., A CORPORATION OF NEW JERSEY.

PERCUSSIVE TOOL.

1,080,096.

Specification of Letters Patent.

Patented Dec. 2, 1913.

Application filed March 28, 1912. Serial No. 686,835.

To all whom it may concern:

Be it known that I, LEWIS C. BAYLES, a citizen of the United States, and resident of Easton, in the county of Northampton and State of Pennsylvania, have invented a new and useful Improvement in Percussive Tools, of which the following is a specification.

This invention has for its object to provide certain improvements in percussive tools, and particularly in valve mechanism therefor.

My invention relates to that type of valve mechanism in which a winged oscillating valve is employed for controlling the admission and exhaust of the motive fluid which operates the work piston of the tool, a novel mounting being provided for the valve whereby its operation is facilitated and its life prolonged.

In the accompanying drawings, Figure 1 is a longitudinal section through the valve chest and seat, a portion of the valve being broken away to more clearly illustrate the spindle on which it is mounted. Fig. 2 is an inverted plan view of the valve and chest, Fig. 3 is a detail, transverse section taken in the plane of the line A of Fig. 1. Fig. 4 is a view in side elevation of the spindle, Fig. 5 is a plan view of the same, and Fig. 6 is a detail view showing more clearly the construction of the inner end of the body portion of the winged valve.

The valve chest is denoted by 1, which chest is provided with a motive fluid inlet 2 leading to an inlet chamber 3 and a motive fluid outlet 4 leading from an outlet chamber 5. Intermediate the inlet and outlet chambers 3 and 5, is located a vertical cylindrical chamber 6, from which cylindrical chamber slots 7 and 8 lead to the inlet and outlet chambers 3 and 5 respectively. These slots 7 and 8 and the intermediate cylindrical chamber 6, all open through the inner face of the valve chest 1, for permitting the ready assembling and removal of the parts as will hereinafter appear.

A double winged oscillating valve is located in the valve chest, the cylindrical body portion 9 of which valve is fitted to the cylindrical chamber 6 in the valve chest. The wing 10 of the valve is located within the slot 7, and the wing 11 of the valve is

located within the slot 8. The slots 7 and 8 and the wings 10 and 11, are so shaped with respect to each other, that the valve is permitted a slight oscillatory movement for alternately opening and closing communication between the inlet chamber 3 and the inlet passages 12, 13, and for alternately opening and closing communication between the outlet passages 14, 15 and the outlet chamber 5.

The valve is mounted upon a spindle 16 which extends axially through the cylindrical body portion 9, concentric with the chamber 6. The outer end of this spindle 16 is extended into a recess 17 at the outer end of the chamber 6, and the inner end of the trunnion 16 may be provided with an enlarged cylindrical base 18 fitted to the inner end of the chamber 6. This spindle is locked against rotative movement by a pin 19 inserted into a recess formed partly in the walls of the base 18 of the spindle and partly in the walls of the cylindrical chamber 6, the body portion 9 of the winged valve being flattened opposite the pinion 19 as shown at 9* for permitting the valve to oscillate on the spindle 16. A positioning means may also be used for insuring the replacing of the valve in the proper position within the valve chest when removed therefrom for any purpose, which positioning means is herein shown as a pin 20, projecting outwardly from the body portion 9 of the valve into a recess 21 in the wall of the cylindrical chamber 6, which recess 21 is of sufficient width to permit the oscillatory movement of the valve. The valve and spindle may be removed from and inserted into the valve chest through the inner face of the chest and the spindle may be readily inserted into and removed from the valve when the chest is removed from its seat.

What I claim is:

1. A valve mechanism including a valve chest having a cylindrical chamber, a winged valve having its body portion fitted to said chamber and a spindle on which the valve oscillates provided with an enlarged head also fitted to said chamber.

2. A valve mechanism including a valve chest having a cylindrical chamber, a winged valve having its body portion fitted to said chamber and a spindle on which the valve os-

cillates, having one end provided with an enlarged head fitted to said chamber and its other end seated in said chest.

3. A valve mechanism including a valve chest having a cylindrical chamber opening through its inner face, a winged valve having its body portion fitted to said chamber and a spindle on which the valve oscillates provided with an enlarged head fitted to the inner end of said chamber.

4. A valve mechanism including a valve chest having a cylindrical chamber opening through its inner face, a winged valve having its body portion fitted to said chamber and a spindle on which the valve oscillates provided with an enlarged head fitted to the inner end of said chamber, said spindle being removable through said inner face of the valve chest.

20 5. A valve mechanism including a valve chest having a cylindrical chamber opening through its inner face, a winged valve having its body portion fitted to said chamber and a spindle on which the valve oscillates provided with an enlarged head fitted to the inner end of said chamber, said spindle and valve being removable through said inner face of the valve chest.

30 6. A valve mechanism including a valve chest having a cylindrical chamber opening through its inner face and a concentric recess at the outer end of the chamber, a winged valve having its body portion fitted to said chamber, and a spindle on which the valve oscillates, having its inner end provided with an enlarged head fitted to the inner end of said chamber and its outer end extended into said recess.

40 7. A valve mechanism including a valve chest having a cylindrical chamber opening through its inner face and a concentric recess at the outer end of the chamber, a winged valve having its body portion fitted to said chamber, and a spindle on which the valve oscillates, having its inner end provided with an enlarged head fitted to the inner end of said chamber and its outer end extended into said recess, said spindle being removable through said inner face of the valve chest.

50 8. A valve mechanism including a valve chest having a cylindrical chamber opening through its inner face and a concentric recess at the outer end of the chamber, a winged valve having its body portion fitted to said chamber, and a spindle on which the valve oscillates, having its inner end provided with an enlarged head fitted to the inner end of said chamber and its outer end extended into said

recess, said spindle and valve being removable through said inner face of the valve chest. 60

9. A valve mechanism including a valve chest having an inner face, a winged valve and a spindle on which the valve oscillates, said spindle and valve being removable through said inner face of the valve chest. 65

10. A valve mechanism including a valve chest, a removable oscillating winged valve therein and positioning means other than the valve wings for insuring the proper replacement of the valve. 70

11. A valve mechanism including a valve chest, a removable oscillating winged valve therein and positioning means other than the valve wings carried by the valve for insuring the proper replacement of the valve. 75

12. A valve mechanism including a valve chest, a removable winged valve therein, a spindle on which the valve oscillates and positioning means other than the valve wings for insuring the proper replacement of the 80 valve.

13. A valve mechanism including a valve chest, a removable winged valve therein, a spindle on which the valve oscillates, means for locking the spindle against rotative movement and positioning means other than the valve wings for insuring the proper replacement of the valve. 85

14. A valve mechanism including a valve chest, having a cylindrical chamber and a recess in the wall of the chamber, a removable oscillating winged valve having a central body portion fitted to said cylindrical chamber and a positioning pin projecting from the central body portion into said recess for insuring the proper replacement of the valve. 90 95

15. A valve mechanism including a valve chest having an inner face and a cylindrical chamber and a recess both open through the said inner face, an oscillating winged valve removable through the inner face of the valve chest and having a central body portion in said cylindrical chamber, and a positioning pin projecting from the central body portion into said recess for insuring the proper replacement of the valve. 100 105

In testimony, that I claim the foregoing as my invention, I have signed my name in presence of two witnesses, this twenty-sixth 110 day of March 1912.

LEWIS C. BAYLES.
